ROBERT SCHORR, OF SAN FRANCISCO, CALIFORNIA.

ROTARY-PUMP MECHANISM.

1,231,072.

Specification of Letters Patent. Patented June 26, 1917.

Application filed June 27, 1916. Serial No. 106,136.

To all whom it may concern:

Be it known that I, ROBERT SCHORR, a citizen of the United States, residing at San Francisco, in the county of San Francisco and State of California, have invented new and useful Improvements in Rotary-Pump Mechanism, of which the following is a specification.

This invention relates to an improved rotary pump mechanism, and the object is to provide mechanism of this character from which the centrally located shaft used in all other pumps of this class will be eliminated, thus permitting of the water being discharged in an unobstructed column; which mechanism will be rapid and self-contained and with bearing surfaces of ample size; which will be of great efficiency, and in which the number of leakage gaps will be reduced and obstructions eliminated, thus obtaining the delivery of a maximum amount of water from a given size of pump runner.

The central shaft employed by all other designs of rotary well pump is an element of great weakness, as it has to be very thin in order to reduce the obstruction caused thereby to a minimum, and as it requires a multiplicity of small bearings, which are somewhat difficult to align. Furthermore, these bearings have to be protected from sand and grit, which are often carried in the water. The proper lubrication of such bearings with certainty is also difficult of accomplishment.

In the accompanying drawing, Figure 1 is a longitudinal vertical section of my improved pump having a rotary suction pipe attached; Fig. 2 is a similar view of a pump 40 with a stationary suction pipe attached.

Referring to the drawing, the runners 1 of the pump are attached, as shown at 2, to a cylindrical housing 3, which in turn is fastened by means of a top casting 4 to an outer pipe 5, which carries at its upper end, above the ground, a pulley 6 for driving said pipe 5, housing 3, and the attached pump runners 1. At suitable intervals bearings 7 for the pipe 5 are supported upon an inside 45 or discharge pipe 8, which is stationary, and secured at the top to a frame 9, secured upon the ground, pump diffusers 10 being supported by said tube 8. Only two bearings 7 are here shown, and they are shown as ball 55 bearings. It is obvious, however, that any

number of such bearings may be used according to the depth of the well, and the design of the bearings themselves can be modified in many ways. The uppermost diffuser 10 has a hub 11 for a stub shaft 12, which is employed for supporting the lower diffusers (one only being here shown). The annular space 13 between the pipes 5 and 8 is made as nearly water-tight as possible by a stuffing box 14, or by any other suitable means. The bottom end of the pipe 5 is bolted to the lowermost runner 1, which also carries a suction pipe 15, which may have a runner or helix 16 at its bottom, or inside its entire length, to propel the water under pressure to the first pump runner. The spaces 13, which may be under pressure, owing to leakage between the runners and diffusers, may communicate by holes 17 and a chamber 15 with the suction space to relieve the pressure on the runners.

Fig. 2 illustrates the same pump, slightly modified to permit of a stationary suction pipe, by extending the stub shaft 12, to carry an inlet casting 18, which has a water seal channel 19 between it and the runner to prevent air leakage, which would reduce the suction lift. Bolted or screwed to this casting 18 is the suction pipe 20, which is therefore stationary, and is in alignment with the diffusers 10 and the fixed discharge pipe 8.

In both forms of the invention a pulley 6 is shown for rotating the outer tube 5, but, instead thereof, gearing can be arranged for direct connection to an electric motor or other source of power. Also the outer pipe can be shortened and geared below the surface of the ground, the gearing being actuated by means of a shaft extending parallel to the discharge pipe 8 and with bearings supported by said pipe. At the upper end of said vertical driving shaft either a pulley or gearing can be used for rotating it.

I have herein illustrated the mechanism as disposed vertically, as is required for wells, but the invention is also adapted for a horizontal or inclined discharge. When so used with a stationary suction pipe it forms a very compact and efficient pump, delivering a large volume of water, as required for drainage and irrigation.

The lubrication of the bearings 7 is effected by feeding oil into the top bearing, the waste or surplus oil therefrom dropping

to the bearing below, and so on until the lubricant fills the annular space between the pipes 5 and 8.

I claim:—

- 5 1. In combination with rotary pumping means, a revolute pipe attached thereto, and provided with means for revolving the same, a stationary discharge pipe within, and concentric with, said revolute pipe, and bearings for the revolute outer pipe supported by and fastened to the stationary discharge pipe.
- 10 2. In combination with rotary pumping means, a revolute pipe attached thereto, and provided with means for revolving the same, a stationary discharge pipe within, and concentric with, said revolute pipe, and means for maintaining the annular space between the outer and inner pipes

free from the water of the source of supply 20 and from the water in the discharge pipe.

3. In combination with rotary pumping means, a revolute upwardly extending pipe attached thereto, and provided with means for revolving the same, a stationary discharge pipe within, and concentric with, said revolute pipe, bearings for the first-named pipe, and means for lubricating the bearings from above.

4. In combination with a rotary pumping 30 means, a revolute pipe attached thereto, and provided with means for revolving the same, a stationary discharge pipe within, and concentric with, said revolute pipe, and a connection between the suction and 35 liquid spaces to relieve the unbalanced pressure on the runners.

ROBERT SCHIÖRR.
